UNITED STATES PATENT OFFICE

2,597,256

POLISHING BELT CONTROL MEANS

Ernest E. Murray, Birmingham, Mich.

Application March 1, 1950, Serial No. 146,953

10 Claims. (Cl. 51—148)

1

The present invention relates to polishing machines, and particularly relates to improvements in machines for polishing flat strips of metal.

The machine of the present invention generally comprises three rolls upon which is mounted a continuous belt having an abrasive on the outer surface. The rolls and belt are mounted on a standard with the rolls rotatable about substantially horizontal axes. The flat strips of metal to be processed are passed under the lowermost roll and against the polishing belt by means of suitable feed rollers, with a billy roll disposed under the lowermost drive roll and spaced therefrom a suitable distance to pass the sheet through the space and against the abrasive belt, and to effect a polish on the upper surface of the sheet.

In order to impart a positive transverse movement to the polishing belt as it rotatably moves about the rolls, the uppermost roll is caused to oscillate about a substantially vertical axis. This oscillation of the roll affects a positive transverse oscillation of the belt. A third take-up roll is provided, which is pneumatically urged against the belt to take up any slack therein, and to maintain a constant pressure on the belt. This third roll is so mounted that upon positive oscillation of the top idler roll, the axis of the third roll is correspondingly shifted so that it remains substantially parallel with the axis of the top idler roll.

The top idler roll is caused to oscillate in response to the position of one edge of the belt. A control system is provided which includes a vacuum box disposed adjacent one edge of the belt, and in the particular embodiment illustrated such vacuum box has a pair of orifices which are spaced a fixed distance apart, and which serve to limit the transverse movement of the belt in both directions as the idler roll is oscillated. The extent of lateral deviation of the belt is dependent entirely upon the distance between these two orifices. Belts of different widths may be used, so long as one edge is disposed to run over the orifices. It is not necessary that the belt be centered on the rolls, as the positive oscillation of the idler roll will affect transverse shifting of the belt from one extreme position to the other, and back again.

One of the primary objects of the present invention is to provide an improved belt tensioning means, whereby a predetermined and constant pressure may be maintained on the belt, in combination with a means for affecting a positive transverse shifting of the belt as it travels in its circuitous path.

2

A further object of the invention is to provide an improved means for effecting the transverse oscillation of the belt.

Other objects of the invention will become apparent from the following specification, the drawings relating thereto, and from the claims hereinafter set forth.

In the drawings, in which like numerals are used to designate like parts in the several views 10 throughout:

Figure 1 is a perspective view of a unit polishing machine embodying features of the present invention;

Fig. 2 is a side elevational view of a portion of the machine shown in Fig. 1, illustrating the relationship of the rolls and the polishing belt;

Fig. 3 is an elevational view taken substantially along the line 3—3 of Fig. 2;

Fig. 4 is an enlarged elevational and cross-sectional view taken substantially along the line 4—4 of Fig. 2;

Fig. 5 is an enlarged cross-sectional view, with parts in elevation, taken substantially along the line 5—5 of Fig. 4;

Fig. 7 is a cross-sectional view taken substantially along the line 7—7 of Fig. 2;

Fig. 8 is a cross-sectional and elevational view 30 taken substantially along the line 8—8 of Fig. 2; and

Fig. 9 is a diagrammatic view illustrating the control for affecting oscillation of the idler roll.

Only one polishing unit is described herein, but it is to be understood that in the normal use of these polishing machines a plurality of such units are arranged in line. Belts of progressively diminishing grain size are employed from the entering end of the assembly to the leaving end, so that sheets may be continuously fed from one end to the other, rough grinding occurring at the entering end with the sheet finally emerging from the last unit with a finished polish. The machine may be employed for use of either dry or wet polishing, but is particularly adapted for wet polishing.

Referring to the drawings, a polishing unit is illustrated which comprises a base 1 having an upstanding frame, generally indicated at 2, mounted thereon. The frame 2 supports a billy roll 3, which idles, having the ends thereof mounted in bearing blocks 4. The frame 2 also supports longitudinally spaced pairs of pinch rollers 5 and 6 which are supported in bearing blocks mounted on the frame. The upper roll 5 is resiliently urged toward the roll 6 and the

sheet to be treated passes between the guide rollers 5 and 6 and over the billy roll 3 in a direction from right to left, viewing Fig. 1.

A standard or housing 7 is also mounted on the frame 1, and the standard 7 serves to mount the polishing mechanism, generally indicated at 8, and also contains the drive means for the rollers. It will be appreciated that the drive means is conventional in construction and will be known and understood by those skilled in the art, so that it is not necessary to disclose such means in detail.

The polishing mechanism 8 comprises three rolls 9, 10 and 11, around which a continuous abrasive polishing belt 12 is trained.

The contact roll 9 is disposed immediately above the billy roll 3, with the axis thereof substantially parallel to the axis of the billy roll, transversely of the sheets to be polished. The contact roll 9 is mounted on a shaft 13 having the ends thereof supported in bearing assemblies supported at the opposite depending ends 14 and 15 of a cantilever casting 16.

The casting 16 is supported at its inner end on the housing 7 for vertical adjustment thereon so as to adjust the roll 9 with respect to the billy roll 3. The inner end of the casting 16 is fixed to a mounting plate, and the vertical ends of the mounting plate are received within grooves of vertical guideways 17 which, in turn, are fixed to the housing 7. The mounting plate and, therefore, the casting 16 may be adjusted vertically on the housing 7 within guideways 17 by means of a rack-and-pinion mechanism (not shown), which is operated by turning a shaft 18. The shaft 18 has the pinion mounted on the inner end, and extends through the front face of the casting projecting therebeyond so that it may be engaged by a suitable tool for vertically adjusting the casting. The casting may be fixed in its vertically adjusted position.

The outer end of the shaft 13, upon which roller 9 is mounted, is rotatably supported within a bearing assembly 19 which is supported on the outer depending leg 14 of the casting 16.

To provide for additional support at the outer end of the roll 9, a link 20 has an opening through the upper end thereof which may be removably positioned over a threaded projection 21 on the outer casing of the bearing assembly 19, and which may be fixed thereon by a nut. The lower end of the link 20 is forked and is pivotally connected to a depending rod 23. The lower end of the rod is threaded and is received through a vertical opening in a mounting bracket 24, which in turn is mounted on the frame 2. The lower end of the link 23 is threaded, and adjusting nuts 25 and 26 are threaded on the rod 23 on opposite sides of the support 24 so that the effective length of the link 23 may be varied according to the vertical adjustment of the roll 9.

In order to remove or apply a belt 12 over rolls 9, 10 and 11, the nut 22 may be removed and the link 20 pivoted away from the projection 21 so that an open space is provided for the belt 12. In normal operation, the supporting links are assembled as shown in Fig. 1 so as to assure stability of the roll 9.

As mentioned above, the top roll 10 is an idler roller, and it is mounted for oscillation about a vertical axis and is provided with mechanism to impart a positive oscillation to the roll 10.

The roll 10 is mounted upon a shaft 27, the opposite ends of which are rotatably received within bearing assemblies 28 and 29. The bear-

ing assemblies 28 and 29 are fixed to the top surfaces of the upwardly extending arms of a U-shaped mounting member 30. The mounting member 30 has a central opening 31 therein and is pivotally supported upon a horizontally projecting mounting member 32 for pivotal movement about a vertical axis.

The outer end of the mounting member 32 has a boss, or vertically cylindrical portion 33, having a vertical opening 34 formed therein. The inner end of the member 32 has an enlarged vertical face, as indicated at 35, and is bolted to the housing 7 above ways 17.

Member 30 is pivotally supported above the boss 33 on a bearing assembly 36 which is supported on an upwardly facing, annular groove 37 formed in the member 32. A vertical pivot pin 38 is received within opening 31 and extends downwardly within the opening 34, and is pivotally connected to the member 32 by bearing assemblies 39 and 40. Thus, the roller 10 and the member 30 are supported on the member 32 and are pivotally connected thereto by means of the pivot pin 38 for oscillation about a vertical axis.

Oscillation is imparted to the roller 10 through a pair of depending arms 41 and 42 at the outer end of member 30. A rocker arm 43 is pivotally mounted intermediate its ends to a U-shaped bracket 44. The bracket 44 is mounted through the bight thereof to the boss 33 of the member 32 by means of screws 45. In order to pivotally mount the arm 43 to the bracket 44, a pivot pin 46 is received through aligned openings 47 and 48 in the outer ends of the arms of the bracket 44, and is received through a vertical pivot opening 49 in arm 43.

The outer end of the pivot arm is indicated at 50, and the inner end indicated at 51', such inner and outer ends being on opposite sides of the pivot 46. The outer end 50 is positioned between the depending arms 41 and 42, as shown in Fig. 5, and is adjustably connected thereto for adjusting the centerline of the roll 10 with respect to the median centerline of the arm 43. In order to provide such an interconnection, the outer end of the arm 50 is bifurcated and receives therein an adjusting wheel 51. A transverse shaft 52 extends through aligned openings in the ends of the member 50 and projects beyond the sides thereof. The shaft 52 has the central portion thereof threaded, as indicated at 53, and is threaded to the wheel 51. Threaded adapters 54 are threaded into aligned openings in the outer arms of the member 50, and are provided with openings therein which support the opposite ends of the shaft 52. One end of the shaft 52 is formed with a longitudinal keyway 55 and a setscrew 56 is threaded into one side of the arm 50 so that the inner end thereof may project within the keyway 55 to prevent rotation of the shaft 52 with respect to the arm 50, but to permit longitudinal movement of the shaft with respect thereto. The projecting end surfaces of the shaft 52 engage balls 57 which are mounted in grooves 58 in the ends of threaded adapters 59. The adapters 59 are threaded into aligned threaded openings in the ends of arms 41 and 42. The balls 57 may be held in the grooves 58 by peening the ends thereof.

By turning wheel 51, the lateral relationship of the arm 50 with respect to the arms 41 and 42 may be varied. As the wheel 51 is rotated, the shaft 52 is caused to move longitudinally with respect to the end of the arm 50 and thus the

arm 50 is shifted in its relative position with respect to arms 41 and 42. The effect of such adjustment 51 is to cause a relative change in the axial position of roller 10 so that, as the arm 43 is rocked to cause oscillation of the roller 10, the relative position of the axis of the roller 10 may be adjusted so that it assumes the proper position with respect to the end positions of the arm 43. For example, with the wheel 51 in its exact central position as the arm 43 is oscillated, the roll 10 will be oscillated to equal distances on opposite sides of its normal median line.

To pivot the arm 43 about pivot 46, and to thereby impart a positive oscillation to the roll 10, a fluid-operated piston and cylinder assembly 60 is connected to the inner end of arm 51'. The assembly 60 comprises a cylinder 61 having the end thereof pivotally mounted to a bracket 62 by means of a pivot pin 63. Bracket 62 is fixed to the hub 33 of the mounting bracket 32. A piston rod 64 projects through the cap end of the cylinder 61 and is pivotally connected to the inner end of the arm 51' by means of a pivot pin 65. Reciprocation of the piston rod 64 affects a rocking of the arm 43 about pivot 46 which, in turn, affects a positive oscillation of the roll 10.

In order to limit the rocking movement of arm 43, a depending boss 66 is formed on the underside of arm 51 and a pair of adjustable screws 67 and 68 are threaded through bosses formed on the lower arm of the bracket 44. By adjusting the positions of screws 67 and 68, viewing Fig. 6, it will be evident that the boss 66 will engage the stops at the limit of its travel and thus limit the extent of oscillation of the roller 10.

The operation of the cylinder assembly 60 is diagrammatically illustrated in Fig. 9, and will be described hereinafter.

For proper operation, and in order to take up expansion in the belt 12 and to assure a proper tension thereon, the takeup roll 11 is provided and is mounted in a manner to be described. It will be appreciated that as the roll 10 is oscillated, the belt will tend to twist and the roll 11 is so mounted that it exerts a uniform pressure against the belt, and also follows the movement of roll 10. That is, as the axis of roll 10 shifts, the axis of roll 11 shifts correspondingly, and such shifting is affected by the belt 12.

Viewing Fig. 3, the roll 11 is an idler roller and is mounted on shaft 10 for rotation therewith. The ends of the shaft 10 are supported within bearing assemblies 71 (Fig. 7) which, in turn, are mounted at the outer ends of mounting arms 72 and 73. The bearing assemblies 71 are of the self-aligning type, known in the art, so that as the arms 72 and 73 are shifted at different angles with respect to each other the shaft 10 on which the roller 11 is mounted may align itself in its mounting bearings.

The arms 72 and 73 are mounted on a cross shaft 74 which is supported in bearing brackets 75 and 76. The bearing brackets 75 and 76 are mounted on and affixed to casting 16.

The arms 72 and 73 are mounted on the ends of cross shaft 74 for independent, relative rotation with respect to each other. Thus, one arm may pivot in one direction and the other arm pivot in the opposite direction according to the force exerted by the twisting action of the belt as the roll 10 is oscillated. The axis of roller 11 will thus remain substantially parallel to the axis of roller 10 at all times during oscillation of roller 10.

A constant pressure is imparted on belt 12

through roller 11 by means of a fluid cylinder and piston assembly, generally indicated at 71. The piston and cylinder assembly 71 comprises a cylinder 78 having one end thereof pivotally connected to a depending bracket 79 by means of a pivot pin 80. The bracket 79 is fixedly mounted to the undersurface of the mounting bracket 32. A piston 81 projects through the opposite end of the cylinder 78 and is pivotally connected to a cross shaft 82. The connection between the shaft 82 and the piston 81 is such as to permit a slight play between the cross shaft 82 and the rod 81. The opposite ends of the shaft 82 are received within recesses 83 of bushings 84, the recesses 83 being aligned and being fixed to the facing surfaces of arms 72 and 73. The connection between the ends of the shaft 82 and the recesses 83 is also a loose connection so that there may be play between the arms 72 and 73 and the shaft 82 as the arms rotate with respect to each other.

The cylinder and piston assembly 71 is provided with the usual inlet and outlet ports and connections which are connected to a suitable source of fluid under pressure for imparting the desired pressure to the cylinder piston, and for thus applying the proper and desired tension on the belt 12.

In the general operation of the device above described, the roll 9 is driven to impart movement to the belt in the direction shown by the arrows in Fig. 1. Rollers 10 and 11 are idler rollers to which rotation is imparted by movement of the belt 12. The roller 10 is oscillated about its vertical mounting axis by oscillation of the inner end of the arm 43. Oscillation of this arm is effected by reciprocation of piston rod 64 of the piston and cylinder assembly 60.

The manner in which the reciprocation of piston rod 64 is affected is diagrammatically illustrated in Fig. 9. Here, the roller 10 is diagrammatically shown to be connected to the piston rod 64 by a pivot arm 43. This interconnection is diagrammatic, and it will be understood that upon pivoting of the arm 43 about a center, indicated at 85, the axis of roller 10 is caused to oscillate about a vertical axis passing substantially through its center.

As the axis of the roller 10 is shifted, the belt 12 will be caused to affect a transverse movement on all of the rollers. That is, when the axis of roller 10 is moved in one direction, the edge of the belt will move toward one edge of the roll; and, when the axis of the roller is reversed, the edge of the belt will move away from that edge of the roll. The extent of this shifting of the belt, or this lateral movement of the edge of the belt, controls the actuation of assembly 60. This is accomplished by a vacuum box 86 which is mounted on casting 16 in a position adjacent the outer edge of the belt 12, as shown in Fig. 1. The vacuum box 86 is positioned in the vertical line of travel between rolls 9 and 10. The box 86 forms an enclosed vacuum chamber having a removable face plate 87, and the box is so positioned that the belt 12 slides against the face plate 87 in its travel. The face plate 87 is provided with a pair of spaced orifices 88 and 89 therein of different sizes, with the larger orifice 89 disposed inwardly from the outer edge of the belt 12. The broken lines passing through the orifices 88 and 89 (Fig. 9) indicate the extent of lateral travel of the belt 12, and it will be appreciated that such travel may be varied by using a face plate 87 with the orifices the desired

distance apart. A constant vacuum is maintained within chamber 86 from a suitable source, and a vacuum conduit 90 communicates with the chamber 86 and with a conventional mercury switch, indicated at 91. As vacuum conditions within chamber 86 change according to the covering and opening of openings 88 and 89 by the belt 12 in its lateral movement, the mercury switch 91 is actuated to actuate in turn a solenoid-operated, hydraulic four-way valve, generally indicated at 92. Such valve 92 is per se well known in the art. Fluid under pressure is supplied the four-way valve through a supply conduit 93, and conduits 94 and 95 are connected to the interior of the piston and cylinder assembly through ports, in the usual way, and are connected to the four-way valve in the usual way. A return conduit 96 is provided which returns from the four-way valve to the tank, and has a needle valve 97 interposed therein.

Upon shifting of the axis of roller 10 in one direction, the edge of belt 12, adjacent the vacuum chamber 86, will move from the position shown by line 98 toward the position shown by line 99. Opening 89 is covered by the belt and opening 88 is open so that the mercury switch 91 is actuated to rock the arm 43 in one direction. The axis of the roller 10 will remain in that position until the edge of the belt starts to cover opening 88. After the opening 88 is closed sufficiently to change the pressure conditions within chamber 86, the vacuum switch 91 will be reversed to shift valve 92 and to effect rocking of the arm 43 in the opposite direction to shift the axis of roller 10 in the opposite direction. This will cause movement of the edge of the belt 12 in the opposite, or return direction, and the roller 10 will remain in that position until port 89 is uncovered to such an extent as to change the pressure conditions in chamber 86 to reverse the mercury switch and shift the four-way valve to affect rocking of the arm 43 in the opposite direction, and thus shift the axis of roller 10 to the opposite position. Repetition of this action affects a positive back-and-forth, transverse movement of the belt 12 on rollers 9, 10 and 11 as the belt is caused to travel in its circuitous path.

Formal changes may be made in the specific embodiment of the invention described without departing from the spirit of the invention, the scope of which is commensurate with the appended claims.

What is claimed is:

1. In a polishing machine comprising a standard, first, second and third rolls mounted on said standard, a continuous polishing belt disposed about said rolls, means mounting said first roll for rotation about a fixed axis, means mounting said second roll for rotation about a shiftable axis, means mounting said third roll for rotation about a shiftable axis, and means to positively shift the axis of the second roll, the engagement of the belt with the third roll causing the shifting of the axis thereof to maintain it parallel with the shifting axis of the second roll.

2. In a polishing machine comprising a standard, first, second and third rolls mounted on said standard, a continuous polishing belt disposed about said rolls, means mounting said first roll for rotation about a fixed axis, means mounting said second roll for rotation about a shiftable axis, means mounting said third roll for rotation about a shiftable axis, and means responsive to the position of one edge of said belt to positively shift the axis of the second roll, the engagement

7 of the belt with the third roll causing the shifting of the axis thereof to maintain it parallel with the shifting axis of the second roll.

3. In a polishing machine comprising a standard, a drive roll, an idle roll, and a third roll, a continuous polishing belt disposed about said rolls in driving engagement therewith, means mounting said drive roll for rotation about a fixed axis, means mounting said idle roll for rotation about a shiftable axis, means mounting said third roll for rotation about a shiftable axis, and means to positively shift the axis of the idle roll, the engagement of the belt with the third roll causing the shifting of the axis thereof to maintain it parallel with the shifting axis of the second roll.

4. In a polishing machine comprising a standard, a drive roll, an idle roll, and a third roll, a continuous polishing belt disposed about said rolls in driving engagement therewith, means mounting said drive roll for rotation about a fixed axis, means mounting said idle rolls for rotation about a shiftable axis, means mounting said third roll for rotation about a shiftable axis, and means responsive to the position of one edge of said belt to positively shift the axis of the idle roll, the engagement of the belt with the third roll causing the shifting of the axis thereof to maintain it parallel with the shifting axis of the second roll.

5. In a polishing machine comprising a standard, a drive roll, an idle roll, and a third roll, a continuous polishing belt disposed about said rolls in driving engagement therewith, means mounting said drive roll for rotation about a fixed axis, means mounting said idle roll for rotation about a shiftable axis, and vacuum actuated means responsive to the position of one edge of said belt to positively shift the axis of the idle roll, the engagement of the belt with the third roll causing the shifting of the axis thereof to maintain it parallel with the shifting axis of the second roll.

6. In a polishing machine comprising a standard, a drive roll, an idle roll, and a third roll, a continuous polishing belt disposed about said rolls in driving engagement therewith, means mounting said drive roll for rotation about a fixed axis, means mounting said idle roll for rotation about a shiftable axis, means mounting said third roll for rotation about a shiftable axis, means to urge the third roll into contact with the belt, and means responsive to the position of one edge of said belt to positively shift the axis of the idle roll, the engagement of the belt with the third roll causing the shifting of the axis thereof to maintain it parallel with the shifting axis of the second roll.

7. In a polishing machine comprising a standard, a drive roll, an idle roll, and a third roll, a continuous polishing belt disposed about said rolls in driving engagement therewith, means mounting said drive roll for rotation about a fixed axis, means mounting said idle roll for rotation about a shiftable axis, means to urge the third roll into contact with the belt and to maintain a substantially constant tension thereon, means responsive to the position of one edge of said belt to positively shift the axis of the idle roll, the engagement of the belt with the third roll causing the shifting of the axis thereof to maintain it parallel with the shifting axis of the second roll.

8. In a polishing machine comprising a stand-

ard, a drive roll, an idle roll, and a third roll, a continuous polishing belt disposed about said rolls in driving engagement therewith, means mounting said drive roll for rotation about a fixed, substantially horizontal axis, means mounting said idle roll for rotation about a substantially horizontal axis and for oscillation about a substantially vertical axis, means mounting said third roll for rotation about a substantially horizontal axis and for shifting about a substantially vertical axis, and means responsive to the position of one edge of said belt to positively oscillate the axis of the idle roll about said vertical axis, the engagement of the belt with the third roll causing the shifting of the axis thereof to maintain it parallel with the oscillation of the second roll.

9. A polishing machine comprising a standard, a drive roll, an idle roll, and a third roll, a continuous polishing belt disposed about said rolls in driving engagement therewith, means mounting said drive roll for rotation about a fixed axis, means mounting said idle roll for rotation about a shiftable axis, means mounting said third roll for rotation about a shiftable axis, pneumatic means to urge the third roll into contact with the belt, and means responsive to the position of one edge of said belt to positively shift the axis of the idle roll, the engagement of the belt with the third roll causing the shifting of the axis thereof to maintain it parallel with the shifting axis of the second roll.

10. In a polishing machine comprising a stand-

ard, a drive roll, and an idler roll, and a third roll, a continuous polishing belt disposed about said rolls in driving engagement therewith, means mounting said drive roll for rotation about a fixed axis, means mounting said idler roll for rotation about a shifting axis, means mounting said third roll for rotation about a shifting axis, and vacuum responsive means having a pair of lateral openings of different relative size spaced a fixed distance apart located adjacent one edge only of said belt means to effect positive shifting of the axis of the idler roll, the engagement of the belt with the third roll causing the shifting of the axis thereof to maintain it parallel with the shifting axis of the idler roll.
